UNITED STATES PATENT OFFICE.

JAMES O. PERKINS, OF AUBURN, NEW YORK, ASSIGNOR TO HAMEL SHOE MACHINERY COMPANY, A CORPORATION OF MASSACHUSETTS.

INSEAM-TRIMMING MACHINE.

1,331,782.

Specification of Letters Patent. Patented Feb. 24, 1920.

Application filed July 20, 1918. Serial No. 245,833.

To all whom it may concern:

Be it known that I, JAMES O. PERKINS, a citizen of the United States, residing at Auburn, in the county of Cayuga and State 5 of New York, have invented certain new and useful Improvements in Inseam-Trimming Machines, of which the following is a specification, reference being had therein to the accompanying drawings.

10 This invention relates to machines intended to remove by a cutting operation surplus material encountered in the manufacture of shoes, and more specifically to a mechanism adapted for use in the making 15 of welt shoes to remove the material projecting above the inseam.

Machines as at present constructed employ knives of various forms for performing the above operation, the knives most 20 commonly employed being either of the band-saw type, or saucer-shaped rotating knives having serrated edges. Machines so constructed have been found to be open to certain objectionable features in practical 25 operation, due particularly to lack of rigidity in the cutter employed, which renders them uncertain in their action, whereby the cutting instrumentality at times fails to remove the desired amount of material, and 30 at other times cuts so deeply as to sever the stitches in the sole, thereby damaging the shoe and rendering it unsalable. Moreover, in machines as at present constructed, the material removed by the cutting instrumentality usually is permitted to drop to 35 the bench or floor in the immediate vicinity of the machine, thus detracting from the appearance of the work-room, and making very frequent cleaning of the same necessary. In accordance with the present invention, the above difficulties have been largely overcome, the machine constructed 40 in accordance with the present disclosure operating in a certain and efficient manner, 45 while at the same time permitting the ready removal from the vicinity of the machine of all surplus material cut from the shoes.

The present invention comprises the employment of a cutting knife of cylindrical 50 form supported for rotation in peripherally arranged bearings, and having one extremity of the cylindrical cutter projecting from

the bearings and provided with a sharpened edge which acts to remove the surplus material from the inseam.

The invention further consists in providing a cutter of the above character of substantially uniform diameter from end to end and having its interior portion entirely unobstructed, whereby cuttings or chips entering the same at one end may be freely discharged at the other end.

The invention further resides in mounting a knife of the above character with its axis inclined downwardly and rearwardly 60 from the cutting edge, whereby chips entering the central portion of the cutter tend, by gravity, to be discharged from the rear end thereof.

The invention also contemplates the provision of a suction tube which may be connected with the ordinary blower system employed in shoe factories, and having operative engagement with the rear extremity of the cutting knife, thus providing a constant draft of air through the same to draw away the chips cut by the blade, and remove them from proximity to the machine.

The invention also comprises the provision of anti-friction bearings for said knife 80 permitting the same to be run at extremely high speed without heating or appreciable friction.

A further feature of the invention consists in furnishing a guard and adjustable 85 guide members adjacent the cutting edge of the knife serving to protect the operator's hand from the action of the same while at the same time guiding the shoe in proper relation to the knife blade.

Another feature consists in the employment in connection with a knife of the above character of an adjustable channel guide provided with an anti-friction roll at its extremity adapted to run within the channel 95 of the shoe adjacent the inseam.

The invention also contemplates the employment of a grinding device which may be thrown into and out of action at the will of the operator, and by means of which the 100 cutter blade may be provided with a true cutting edge without removing the same from the machine.

Other and further objects and advantages

of the mechanism disclosed will be herein-after described in detail, and particularly pointed out in the claims, reference being had to the accompanying drawings as showing a preferred embodiment thereof, and in which,—

Figure 1 is a side elevation of the machine, the upper portion thereof being in section,—

10 Fig. 2 is a partial front elevation to large scale and at right angles to the axis of the cylindrical cutting blade,—

15 Fig. 3 is a plan view showing the cutting edge of the knife and the upper guide carrier, and

Fig. 4 is a partial front elevation to small scale illustrating the arrangement of the knife grinder mechanism.

1 is the base of the machine upon the top 20 of which is mounted, as by means of bolts 2, a bracket 3, carrying a head or frame 4, the head or frame 4 being bored out longitudinally at 5 for the reception of the operative elements of the machine to be hereinafter 25 described.

6 is a cutter holder or carrier in the form of a hollow sleeve provided near its central part with a portion of greater diameter as indicated at 7, thereby providing shoulders 30 8, 8^a. The exterior surface of the cutter carrier at 9, 9^a is screw threaded, that portion of the carrier which projects beyond the threaded portion 9 being split or slotted at one or more points as indicated at 10. 35 Fixed to the carrier at its central enlarged portion is a pulley 11, which may be grooved as shown at 12 for engagement with a driving belt of usual type. The head or frame 4 is slotted at its lower central portion upon 40 each side, as illustrated, at 13, to provide for the passage of the belt toward and from the pulley.

14, 14^a are a pair of washers spaced apart at a suitable distance to permit the location 45 of the pulley 11 between them, said washers having openings 15, 15^a therein of slightly greater diameter than the diameter of the central portion of the carrier, these washers being held in fixed position in the 50 frame or head by means of set screws or other suitable devices 16, 16^a. 17, 17^a each indicate one element of a ball race, such element being in the form of a ring having a central bore adapting the same to fit 55 snugly over the small portion of the cutter carrier, said ball races being held in fixed relation to the carrier by means of nuts 18, 18^a having threaded engagement with the screw-threaded portions 9, 9^a of the carrier, 60 and which nuts serve to hold said ball race members firmly against the shoulders 8, 8^a of the carrier. 19, 19^a are the co-operating members of the ball race, the respective pairs of members serving to provide guide- 65 ways in the usual manner for a series of

balls 20, 20^a, the outer ball race members 19, 19^a being of such external diameter as to bear against the interior of the bore 5 formed in the head or frame 4. 21, 21^a indicate a second pair of washers located externally of the ball race members 19, 19^a, and serving to retain the same in proper position in the frame or head, said washers being of an internal diameter slightly greater than the external diameter of nuts 18, 18^a, and being held in fixed relation in the frame by means of set screws 22, 22^a.

As will be noted from inspection of the drawings the bracket 3 is so arranged that the bore in the head or frame is positioned 80 with its axis inclined downwardly from front to rear and thus the cutter carrier is similarly positioned. 23 is a hollow cylindrical cutter of substantially uniform diameter from end to end, and having its rear extremity inserted within the split forward end of the cutter carrier. 24 is a manually adjustable nut engaging the outer part of the screw-threaded portion 9 of the carrier, said nut being adapted upon proper manipulation of the same to contract the split end portion of the carrier, thereby to firmly clamp the cutter in place therein. The outer extremity of the cutter is ground as at 25 to form a blade, the edge of which, as herein shown, is circular and continuous. It is not to be understood, however, that the invention is limited to the employment of a straight-edged blade, as is herein disclosed, as blades having serrated edges 95 might be substituted therefor, if desired.

27 is a bracket carried by the head and which may be integral therewith if desired, said bracket at its free extremity lying closely adjacent the end of the cutter member and being provided with a guard 28 extending around the edge of the cutter member throughout substantially a semi-circumference thereof, the exact extent of the guard, however, being immaterial. The forward surface 29 of said guard is located slightly beyond the cutting edge of the knife, thereby serving to prevent accidental injury to the operator.

30 is a slot formed in the outer edge of the guard providing a guideway wherein is adjustably supported as by means of a screw passing through a slot 32 in the same, a channel guide 33, said guide extending circumferentially beyond the extremity of 115 the guard to a point slightly below the horizontal diameter of the cutter, the precise position, however, of the extremity of said guide being determinable at the will of the operator. 34 is a roll freely rotatable upon 120 the extremity of said guide and serving to lessen the friction of the shoe in moving over the same. 35 is a guide carrier pivotally mounted, as by means of a screw 36, on the guard member near its central portion, 130

said guide carrier extending circumferentially along the edge of the blade, and having its free extremity opposed to the extremity of the guide 33. As indicated in 5 the drawings, the guide carrier 35 is of substantially the same internal diameter as the cutter, but by reason of the mounting of the same at a substantial distance from the edge of the cutter, the free extremity of said carrier, when in normal position, overlaps and lies across the edge of the blade, the extremity of said carrier at 37 forming a 10 guide for engagement with the outer surface of the inseam. 15 38 is a lip projecting downwardly from the outer surface of the guide carrier near its extremity and overlying the outer surface of the cutter, thereby serving to protect the welt from injury by the latter. 39 is a 20 spring having one end fixed to the upper surface of the guard near its lower extremity as by means of a screw 40, and having its upper end formed for ready engagement with a pin 41 outstanding from the surface 25 of the guide carrier, said spring thus normally tending to move the free extremity of the guide carrier toward the coöperating extremity of the channel guide. 42 is a boss projecting from the upper edge of the 30 guide carrier, and having a screw-threaded opening 43 therein, in which is mounted a thumb screw 44, the end of which is adapted to engage against the outer edge of the guard member, thereby serving to adjustably 35 limit the swinging movement of the guide carrier about its pivotal support, and thus determining the degree of separation of the two guide members.

As shown herein, the rear extremity of the 40 cutter holder or carrier projects downwardly beyond the nut 18^a and associated therewith is a suction pipe 72, said suction pipe being intended for connection with the usual suction blower system commonly employed in 45 shoe factories for removing surplus cuttings and material from the machines there used. This pipe as shown comprises a collar 73 at its extremity closely surrounding the extremity of the cutter holder or carrier to 50 provide a substantially air-tight connection between the two, this arrangement serving to provide for the production of a strong draft of air rearwardly through the center of the cutter and cutter carrier, whereby 55 cuttings removed by the edge of the cutter are caused to flow rearwardly through the interior thereof and away from proximity to the machine.

Formed in the bracket 3 is a transverse 60 bore 45 in which is fixedly supported a shaft 46 upon which are mounted for free rotation a pair of idler pulleys 47, 47^a, the pulley 47 being retained upon the shaft by means of a collar 48, said idler pulleys 47, 47^a serving 65 to direct the driving belt from a driving

pulley supported in the base of the machine, and not herein shown, to and from the drive pulley 11. As herein shown, the left hand extremity of the hub of pulley 47^a is provided with a clutch element 49 adapted for 70 engagement with a coöperating clutch element 50 formed upon the adjacent hub of a pulley 51 also loosely mounted upon the shaft 46. Interposed between said pulleys 47^a and 51 is a spring 52 acting normally to 75 separate the clutch elements. The shaft 46 projects beyond the pulley 51 and is supported by means of a bracket 53 outstanding from the bracket 3, the shaft projecting beyond 80 said bracket and serving to pivotally support a bracket arm 54 swingable thereon, but held in position by means of a fixed collar 55. Said bracket arm is bifurcated at its upper end 56 to provide spaced apart bearings 57, 57^a in which is mounted a shaft 85 58, said shaft being retained within said bearings by means of fixed collars 59, 59^a.

Upon the free extremity of said shaft and outside the collar 59 are loosely mounted a pair of connected pulleys 60, 60^a, said pulleys being retained upon the shaft by means of a fixed collar 61. Pivoted for free swinging movement upon the shaft between the bearings 57, 57^a is a secondary bracket 62, provided at its free extremity with 90 spaced apart bearings 63, 63^a, within which is rotatably mounted a shaft 64. Between said bearings is located a pulley 65 fast to the shaft, and serving to retain the shaft within its bearings. Upon the free extremity thereof, beyond the bearing 63 is fixed an abrasive wheel 66, said wheel being of any usual and well known construction. 95 67 is a belt passing around the pulleys 51 and 60, and 67^a is a belt passing about the 100 pulleys 60^a and 65.

The bracket arm 54 is normally held in rearward position by gravity, resting against a stop 68 carried by the frame, the secondary bracket 62 being provided with a stop 69 110 limiting the downward pivotal movement of the same about its supporting shaft. 70 is a handle projecting from the bracket 62 and permitting the operator by manual manipulation to draw the bracket arms forwardly 115 from their normal position of rest to a position in which the abrasive wheel may engage the edge of the rotating cutter. The operator will at the same time by manipulation of a suitable clutch handle 71 move the 120 pulley 51 longitudinally of the shaft 46, whereby to engage the coöperating clutch elements 49, 50, thus serving to rotate the pulley 51 and through the belt connections to drive the abrasive wheel 66, thus acting 125 to grind the edge of the cutter to secure proper cutting action of the same.

In order to permit movement of the abrasive wheel into contact with the knife blade, it is necessary that the guide carrier 130

be removed from the path of such abrasive wheel, and the above described connection of the spring 39 thereto by means of the pin projecting from said guide carrier permits ready disengagement of the spring therefrom whereupon the guide carrier may be thrown back out of the path of said abrasive wheel.

In the normal operation of the machine, it being assumed that the cutter has been properly ground to secure a sharp cutting edge, and that the channel guide has been adjusted in accordance with the character of the work to be operated upon, the operator will insert the roller carried by the channel guide into the channel or against the inside of the lip of the insole, the inseam projecting into the space between the channel guide 33 and the outer, seam-guide 37, the latter resting against the outer surface of the inseam, and aiding in supporting and guiding the same. As the cutting blade rotates it serves to remove the surplus material projecting above the seam by a smooth and uniform cutting action, and during such action the operator manipulates the shoe to traverse the inseam over the cutting edge, the chips or surplus material removed by the cutting action being drawn downwardly into the interior of the cutter, and being discharged from the rear extremity thereof, it being noted that the interior of the cutter and of the cutter holder are free and clear from obstructions from end to end, thus permitting the chips to pass freely through the same. Due to the rigid character of the cutting blade the action of the same is certain, the depth of cutting being dependent upon the relative positions of the two guide members and being fully under control of the operator, the machine acting at the same time to remove all cuttings or chips from the near proximity of the machine, thus keeping the floor of the work room in neat condition.

While the above described structure is a preferred form of my device, it is not to be understood that the invention is to be limited to the specific details herein disclosed, but it is intended to cover all such changes and modifications as may fall within the scope of the appended claims.

Having thus described the invention and a preferred embodiment of the same, together with the operation thereof, what I claim and desire to secure by Letters Patent of the United States is,—

1. In an inseam trimming machine, a frame, a cutter holder mounted for rotation therein and provided with cutter gripping means, and a hollow, cylindrical cutter mounted within said gripping means,—said cutter being open and unobstructed from end to end.
2. In a leather working machine, a hol-

low cylindrical member having one extremity sharpened to form a cutting edge, and having both extremities open and unobstructed, clamping means engagable with the outer surface of said member, and means for rotatably supporting and driving said clamping means.

3. In a machine for trimming inseams, a frame, a cutter holder mounted for rotation within said frame and having its axis inclined from front to rear, clamping means carried upon the forward extremity of said holder, a hollow cylindrical cutter mounted therein, and means for rotating said holder.

4. In an inseam trimming machine, in combination, a frame, bearing members carried by said frame, a cylindrical open-ended cutter mounted for rotation in said bearings and provided at one extremity with a cutting edge, and means associated with said cutter for producing a draft of air through the same and rearwardly from the cutting edge.

5. In an inseam trimming machine, in combination, a frame, a cylindrical, open-ended cutter rotatable therein and having one extremity provided with a cutting edge, and a suction conduit having connection with the opposite extremity of the said cutter and arranged to convey away the chips formed in the operation of the machine.

6. In an inseam trimming machine, in combination, a hollow cylindrical member having one end sharpened to form a cutting edge, a fixed guard member adjacent to and extending along a portion of such edge, and an adjustable channel guide mounted upon said guard member.

7. In an inseam trimming machine, in combination, a hollow, cylindrical cutter providing an endless cutting edge, a fixed cutter guard adjacent said edge, and means carried by said guard and providing a guide for contact with the exterior edge of the inseam.

8. In a machine of the class described, in combination, a frame, a cylindrical, open-ended cutter rotatably supported therein, and having an endless cutting edge, a bracket fixed to said frame, a guard member carried by said bracket and located adjacent said cutting edge and extending circumferentially thereof, and an outside seam guide pivotally supported upon said member.

9. In combination, in an inseam trimming machine provided with a cylindrical, open-ended cutter having an endless cutting edge, a guard member adjacent said edge and extending circumferentially thereof, a guide carrier provided with a seam guide pivoted adjacent one extremity of said guard and extending circumferentially along the cutting edge beyond said extremity, resilient means tending to swing said guide toward

and across said edge, and adjustable stop means for limiting such swinging movement.

10. In a machine of the class described, in combination, a frame, a cylindrical cutter rotatable in said frame and having an endless cutting edge, a guide carrier arranged to move toward and from said cutter and extending circumferentially of said edge, resilient means normally tending to swing said carrier toward said cutter, said means being disengageably connected to said carrier.

11. In an inseam trimming machine, in combination, a rotary cylindrical cutter member having an endless cutting edge, abrasive means movable toward and from said edge for grinding the same, a guide carrier normally positioned adjacent said

edge and in the path of movement of said abrasive means, and means for movably supporting said guide member to permit retraction of the same from the path of the abrasive means.

12. In an inseam trimming machine, in combination, a hollow cylindrical open-ended member having formed upon one end thereof a cutting edge, a fixed guard member adjacent said edge and extending throughout substantially a semi-circumferential segment thereof, a channel guide mounted adjacent one end of said guard, an exterior, seam-guide supported adjacent the opposite extremity of said guard, and means permitting relative adjustment of said guides.

In testimony whereof, I have signed my name to this specification.

JAMES O. PERKINS.
